UNITED STATES PATENT OFFICE.

LEWIS A. JARVIS, OF GRAND RAPIDS, MICHIGAN.

WATER GAUGE FOR AUTOMOBILE RADIATORS.

Application filed May 1, 1922. Serial No. 557,618.

This invention relates to improved water gauges for automobile radiators.

The object of the invention is to provide a simple and effective device especially adapted to die casting construction by which the water level will be effectively registered by the float means and also the boiling indicated by agitation of the vane.

Objects pertaining to details and economies of construction and operation will definitely appear from the detailed description to follow.

I accomplish the objects of the invention by the devices and means described in the following specification. The invention is clearly defined and pointed out in the claims.

A structure which is a preferred embodiment of my invention is clearly illustrated in the accompanying drawing, forming a part of this application, in which:

Fig. I is a plan view of my structure.

Fig. II is a front elevation view with the radiator cap part in vertical detail section 25 on the irregular line 2—2 of Fig. I.

Fig. III is a detail central vertical sectional view on line 3—3 of Figs. I and II showing details of construction.

Fig. IV is an enlarged detail sectional view on line 4—4 of Fig. I showing the lock means for retaining the cap effectively in position.

In the drawing the sectional views are taken looking in the direction of the little arrows at the ends of the section lines and similar numerals of reference refer to similar parts throughout the several views.

The parts of the drawing will be considered by their numbers. 1 is a radiator cap having laterally projecting ornamental arms 2. It is formed to cap over and fit upon the radiator neck 3 to which it is secured in the desired position by the set screw 3', the head of which is broken off at the time of installation. The screw is necked in a well known manner, see dotted lines in Fig. IV, to that end. 4 is a vertical tube tightly fitting a perforation in the said cap 1, being suitably enlarged and shouldered at 5 to insure its effective seating. A jammed lock nut 62 is screwed on the tube 4 against the inside of the cap 1. This effectively retains the dial member 6 of which the tube 4 constitutes a shank in correct position. The dial member 6 is preferably triangular in form with apex up

like an arrow as indicated and with a vertical central slot 7 therethrough which guides and supports the indicating vane 8. The dial member 6 is, in the embodiment 60 illustrated, provided with a relatively heavy surrounding rim 61. The indicating vane 8 is adapted to engage the opposite edges of the slot and move up and down the slot and thus indicate the level or condition of the water or other liquid within the radiator. The vane 8 is carried on the upper end of a rod 9 projecting up from below which is connected by a suitable link 9' to a float 10 at its lower end. The float 70 10 is disposed in a chamber 11 made up of a section of tube threaded on to the lower end of tube 4. The lower end of tube 4 thus forms a limiting stop to the upward movement of the float 10. The upper end of the float is in the form of a valve and the lower end of tube 4 is a valve seat to prevent slopping of the water up to the dial. The lower end of this tube 11 is sharpened to perforate 80 if need be the deflector plate of thin sheet metal found in many automobile radiators. By grasping the handles 2 the chamber 11 can be forced through the thin deflector plate or force it to one side and displace the overflow pipe if need be.

To provide a proper opening for filling the radiator without removing the cap I provide a cover 12 which is pivoted at 13 at one side and retained by spring friction ball 14 at the opposite side.

The triangular form of dial head is of advantage in that while it presents a neat appearance it is of such form as not to be readily injured and is very staunch.

I have described the improved indicator 95 in its preferred form. However, I desire to state that it may be varied considerably without departing from my invention.

Having thus described my invention, what I claim as new and desire to secure by 100 Letters Patent, is:

1. In a structure of the class described, the combination of a radiator cap having a hole therein and also having a filling opening at one side provided with a closure, the opening and hole being on opposite sides of the center of the cap, a dial member provided with an integral tubular shank disposed through said hole in said cap and secured therein, said dial member comprising a triangular frame and a weblike plate within the frame having a vertical slot therein, a

float tube secured to the lower end of said shank, a float disposed in said tube, a vane 5
slidable in said slot in said dial member, and a rod connected to said float and carrying
said vane.

2. In a structure of the class described, the combination of a radiator cap having a
hole therein, a dial having a vertical slot 10
therein and provided with a tubular shank
disposed through the hole in and secured to
said cap, the lower end of said shank constituting a valve seat, a float guide tube se-

cured to the lower end of said shank, a float 15
disposed in said tube and coacting with said
valve seat when the float is in raised posi-
tion, an indicator vane movable in said slot
of said dial, a supporting rod on which said
vane is mounted guided in said shank, and
a connection for said float to said rod per-
mitting the float to act as a valve. 20

In witness whereof, I have hereunto set
my hand.

LEWIS A. JARVIS.
